UNITED STATES PATENT OFFICE.

JOHN HAWTHORN AND JOHN PEMBERTON LIDDELL, OF NEWTOWN, NEW MILLS, ENGLAND.

APPARATUS FOR WASHING PRINTERS' BLANKETS.

SPECIFICATION forming part of Letters Patent No. 603,638, dated May 10, 1898.

Application filed July 30, 1896. Serial No. 601,119. (No model.)

To all whom it may concern:

Be it known that we, JOHN HAWTHORN and JOHN PEMBERTON LIDDELL, subjects of the Queen of Great Britain, residing at New-
town, New Mills, near Stockport, in the county of Chester, England, have invented certain new and useful Improvements in Apparatus for Washing and Cleansing Calico-Printers' Blanketing, of which the following is a speci-
fication.

Our said invention relates to improvements in apparatus for washing and cleansing calico-printers' blanketing.

The invention refers to that class of appa-
ratus in which one side only of the blanketing is washed, so as to save the blanketing from unnecessary saturation, and thus effect economy in drying.

According to our invention that side of the blanketing which is subjected to the washing operation is liberally treated with water by the aid of swilling-brushes or their equivalents, while at the same time by our improved arrangements less water is used or wasted than formerly, and the supply is so arranged that the freshly-introduced water meets the blanketing as it leaves the apparatus, while the foul water encounters the blanketing as it enters the machine. Thus the water is used to the best advantage.

Our invention will be more easily under-
stood by a reference to the annexed two sheets of drawings, which illustrate our invention.

Figure 1 is a vertical longitudinal section of our improved apparatus fashioned with an inclined trough or trough-bottom. Fig. 2 is a similar view with a horizontal trough.

In carrying our invention into effect in the manner shown by Fig. 1 we provide an in-
clined oblong trough or casing *a* to contain or support the brushes *b* *b'* *b''* and backing-
rollers *c*. In the said inclined casing we mount two, three, or any greater number of
backing-rollers *c* *c'* *c''* and also guiding or di-
verting rollers *d*, around which the blanketing *e* is carried as it passes through the ma-
chine. These backing and carrying rollers *c* *c'* *c''* lie successively at about the same rela-

tive angle as the floor of the apparatus. Above the last backing-roller *c''* we mount a 50 drawing-cylinder *f*, around which the blanketing is led as it leaves the machine. The other backing and guiding rollers are not driven, but this last drawing-cylinder *f* is positively driven, so as to draw the blanket- 55 ing *e* through the machine, the strain on the blanketing keeping it close against the back-
ing-rollers *c* *c'* *c''* and so presenting it under favorable conditions to the revolving scrub-
bing and swilling brushes *b* *b'* *b''*. 60

From the drawing-cylinder the blanketing is led over guide-rollers *g* to the ordinary drying-cylinders, which do not appear in the drawings. We place the first revolving swilling and scrubbing brush *b* beneath the first 65 backing-roller *c*, and we also place the swilling and scrubbing brushes *b'* *b''* between the other two backing-rollers *c'* *c''*, the said swilling-brushes being so situated as to act simul- 70 taneously at both sides upon the blanketing as it is stretched around the rollers. Thus each brush after the first practically performs the work of two. A final cleansing and moisture-removing brush *h* revolves in contact with the blanketing as it passes around the 75 last backing-roller *c''* of the series, this latter brush *h* revolving at a considerably-increased speed as compared with the other brushes.

As to the distribution of the water-supply we preferably arrange spurt-pipes *i* *i* between 80 the first and second and the third backing-rollers. The water from the first spurt-pipe *i* is dashed on the blanketing *e* as it passes around the first roller *c* and removes the bulk of the color and matter which has been loos- 85 ened and already partly removed by the swilling and scrubbing brushes *b* *b'*. The water so dashed on the blanketing falls into the bottom of the casing and is collected in a trough *k*, within which the intermediate 90 swilling and scrubbing brush *b'* works. This swilling-brush *b'* makes lavish use of the wa-
ter in the trough *k*, raising it and dashing it against the blanketing *e*, with which it is in contact. The water overflowing from this 95 latter trough *k* enters a lower trough *k'*, in

which the first swilling and scrubbing brush b revolves, also applying the water to the blanketing. From this last trough the water finally overflows and escapes by an outlet l .

5 In addition to the two swilling-troughs k and k' we might have a third trough k^2 beneath the brush b^2 , as indicated in dotted lines in the drawings; but in practice we prefer to dispense with this additional trough. The 10 said troughs, compartments, or pools k k' are conveniently formed by partitions o , extending across the casing and secured by angle-irons o' ; but they may be formed in any other suitable manner.

15 The progress of the blanketing through the machine is as follows: Entering from the printing-machine in the direction of the arrow it passes around the first backing-roller c . Here it encounters the first swilling and 20 scrubbing brush b , which dips into the trough k , and which removes the great bulk of the dirt and color from the surface of the blanketing. In practice we find that this brush removes and projects the bulk of the dirt on 25 the blanket against the lower end of the casing, thus avoiding excessive fouling of the water in the trough k . The blanketing in its further progress around the same backing-roller c is next acted upon by the one side of

30 the intermediate revolving swilling and scrubbing brush b' , the latter brush dipping into the trough k' above the first trough, and which receives the water falling from the spurt-pipe i and also the water running from the upper 35 end of the machine. The said swilling and scrubbing brush b' operates on the blanketing not only as it ascends to the diverting or guiding cylinder d , but also as it descends and passes around the succeeding backing-roller

40 c' , the brush acting simultaneously against both backing-rollers. In the same manner the blanketing in its continued progress through the apparatus is next subjected to the action of the brush b^2 , which operates on 45 the blanketing against both the rollers c' and c^2 . The spurt-pipe i' also douches the blanketing above the brush b^2 . The blanketing at this point being almost completely cleansed, the douche from the spurt-pipe i' gives a final 50 swill to the surface of the blanketing. Lastly the blanketing as it proceeds around the roller c^2 is subjected to the rapidly-revolving moisture-removing brush h , which removes all surplus moisture from the face of the blanketing, and renders it much more easily and 55 quickly dried by the drying-cylinders.

The swilling and scrubbing brushes b b' b^2 are revolved at a speed sufficient to exercise a scrubbing and swilling effect upon the 60 blanketing, but not so fast as to throw the water out of the troughs into which they dip. The water is lifted from the trough by the revolving brushes and applied plentifully to the blanketing, the same water being used 65 again and again, so that we use the water thoroughly and none is wasted. As the water from the trough above overflows into the

trough beneath it in turn overflows and allows the foul water to run to waste. There may be one, two, or any greater number of swilling and scrubbing brushes with corresponding water-troughs, but we consider two sufficient. The water from the spurt-pipes keeps the troughs full and plays upon the blanketing as it passes around the backing-rollers. The 75 spurt-pipe i' gives a final swill with clear water to the blanketing, and then follows the action of the brush b^2 beneath, and lastly that of the more rapidly revolving and final moisture-removing brush, which wipes the surface 80 of the blanketing free of moisture before it passes around the drawing-roller and then away from the apparatus. We might employ only one spurt-pipe—viz., the spurt-pipe i' —in which case the whole apparatus would be 85 served from this single supply, and by arranging the backing-rollers, as described, at successively lower angles and providing the aforesaid overflow-compartments and swilling and scrubbing brushes the water is used 90 again and again, the fouler water meeting the fouler portions of the blanketing, as hereinbefore described. We might, however, as aforesaid, multiply both spurt-pipes and cleansing-brushes.

In Fig. 2 the trough a , instead of being arranged at an incline, as in Fig. 1, is set horizontally. In other respects the apparatus is almost identical with that shown in Fig. 1. The water from the spurt-pipes i' plays upon the blanketing e as it passes around the backing-rollers c' and falls into the trough k^2 . The swilling and scrubbing brush b^2 dips into the water in the trough k^2 and swills and scrubs the blanketing. From the trough k^2 the water overflows over the partition o into the trough k' , into which the swilling and scrubbing brush b' dips. This brush swills and scrubs the blanketing e against both the backing-rollers c' and c . From the trough k' the water flows over the next partition o into the trough k , in which the brush b revolves, swilling and scrubbing the blanketing as it passes around the first backing-roller c . The water then overflows into the end of the casing and is led away through the outlet l . As shown in the drawings, the partitions o are made successively lower toward the end at which the blanketing enters, so as to let the water overflow from trough to trough, and to compensate for the successive lowering of the water-levels in the compartments or pools k^2 , k' , and k we successively increase the diameter of the swilling and scrubbing brushes b^2 , b' , and b . We might also, to preserve the same 125 surface speed in all, drive the said swilling and scrubbing brushes at different speeds, corresponding to their diameters. In other respects the construction and operation of the apparatus are precisely as indicated in Fig. 1. 130

What we claim as our invention is—

The improved apparatus for washing calico-printers' blanketing consisting of the inclined casing a , furnished with overflow com-

partments or pools, swilling and scrubbing brushes dipping into the said compartments, backing and guiding rollers to carry the blanketing, spout-pipes to supply water or other cleansing fluid, and a moisture-removing brush, all arranged combined and acting substantially as hereinbefore set forth and as illustrated.

In witness whereof we have hereunto set our hands in presence of two witnesses.

JOHN HAWTHORN.

JOHN PEMBERTON LIDDELL.
